HANGER FOR COAT AND TROUSERS OR SIMILAR ARTICLE

Alphonsus Philip Gately, Long Beach, Calif.

Application June 1, 1948, Serial No. 146,697

Term of patent 7 years

(Cl. D80—8)

To all whom it may concern:

Be it known that I, Alphonsus Philip Gately, citizen of the United States of America, residing in the city of Long Beach, in the county of Los Angeles, State of California, have invented a new, original, and ornamental Design for a Hanger for Coat and Trousers or Similar Article, of which the following is a specification, reference being had to the accompanying drawing forming a part thereof.

Fig. 1 is a front elevational view of a hanger for coat and trousers or similar article showing my new design; and

Fig. 2 is an end elevational view of the device.

I claim:

The ornamental design for a hanger for coat and trousers or similar article, substantially as shown.

ALPHONSUS PHILIP GATELY.
